UNITED STATES PATENT OFFICE.

CHARLES W. BECK, OF NEW YORK, N. Y., AND WILLIAM C. HOMAN, OF MERIDEN, CONNECTICUT, ASSIGNEES TO EDWARD MILLER & COMPANY, OF MERIDEN, CONNECTICUT, A CORPORATION OF CONNECTICUT, AND THE ACETYLENE GENERATOR MANUFACTURING COMPANY OF WEST VIRGINIA, OF NEW YORK, N. Y., A CORPORATION OF WEST VIRGINIA.

ACETYLENE-GAS GENERATOR.

SPECIFICATION forming part of Letters Patent No. 710,559, dated October 7, 1902.

Application filed December 13, 1900. Serial No. 39,589. (No model.)

To all whom it may concern:

Be it known that we, CHARLES W. BECK, residing at New York city, New York, and WILLIAM C. HOMAN, residing at Meriden, 5 Connecticut, citizens of the United States, have invented certain new and useful Improvements in Acetylene-Generators, of which the following is a full, clear, and exact description.

Our invention relates to certain new and useful improvements in gas-generators particularly useful in lamps and small generating apparatus. In devices of this character the gas is automatically generated and fed to 15 the burner; and it is the object of our invention to provide a simple and effective means whereby the user may manually shut off the flow of gas through the outlet-pipe and at the same time shut off the communication between the gas-generating elements, so that there will be no after generation of gas. When it is again desired to use the generator, the user may open the gas-outlet, whereupon the communicating passage between the gas- 25 generating elements is opened, so that gas may again be generated.

In the drawings we have illustrated a generator in the form of a lamp, in which automatic means is provided whereby the gas-generating elements may be brought together so as to gradually produce the proper quantities of gas. This, it will be seen, in the particular form shown is accomplished by automatically controlling a valve between the carbid-chamber and the fluid-chamber, the said valve being controlled by a diaphragm. The pressure of the gas within the lamp varies the operative position of the diaphragm, so that it in turn may regulate the position of 35 the feed-valve for the carbid.

In the drawings, Figure 1 is a side elevation, partly in section, of a portion of a lamp provided with our improved controlling ap-

paratus. Fig. 2 is a plan view of our controlling apparatus and the parts associated therewith, partly in section. Figs. 3 and 4 are detached views of details of construction.

A is a water-reservoir. B is a carbid-receptacle above said reservoir.

C is a feed-valve.

D is a valve-seat.

E is a valve-stem connected to a diaphragm F' of a collapsible gas bag or chamber F.

F' is a partition within the generator, forming a space for the gas-bag.

G is a spring connected to the gas-bag in such a way that it will cause the same to collapse, except when under pressure.

H is a tube surrounding the valve-stem E and spring G, partly as a protection therefor and partly as a supporting means for the stationary end of the spring G. The tube H forms a gas-passage into the gas-chamber F, and it may have supplemental gas-passages H', if desired.

I is a lever connected with the movable portion of the gas-chamber—the diaphragm F'. This lever I is fulcrumed at J. In the drawings this lever is shown to be bifurcated, so that its two forked members engage on opposite sides of the valve-stem, which is shown as passing through and fixed to the diaphragm F'. At a suitable point on the lever-arms I there is an arched portion or yoke I'. (See Fig. 4.)

K is a valve-rod.

K' is a valve.

L is a valve-seat in a passage for the gas leading from the gas-chamber F to the burner M. N is a flexible tube which may form part 80 of said gas-passage.

In order to render the generator perfectly safe, we have devised a means whereby the carbid-feed is checked at the same moment the gas is turned off in the outlet-pipe, so that 85 after generation is prevented. Consequently

the lamp may be set to one side with perfect safety until it is desired to use it again. We have described the means for turning off the gas in the outlet-passage, and we will now 5 proceed to describe the means coacting therewith for closing the carbid-feed.

In the drawings, O is a cam carried by the valve-stem K, which cam co-operates with the yoke I', so that when the valve-stem K is rotated 10 it will quickly lift said yoke, and thereby the lever-arms I, which in turn quickly expand the gas-bag G, moving the valve-stem E and bringing the valve C into contact with the valve-seat D, thereby shutting off communication 15 between the carbid and fluid chambers and preventing the after generation of the gas. In a lamp this quick expansion of the collapsible gas-chamber causes a slight suction, which extinguishes the flame 20 at the burner instantaneously. Inasmuch as the valve K' closes the passage to the burner, any gas that may be contained within the lamp is imprisoned until it becomes desirable to light the lamp again, whereupon the moment 25 the valve is opened this retained or imprisoned gas flows to the burner and may be instantly ignited. This is a desirable feature, because it is not necessary to wait for the generation of the new gas-supply.

30 While we have shown and described this invention as in connection with a gas-lamp, it is obvious that it has its advantages in connection with acetylene-gas generators at large.

35 The partition F² forms a separate space for the collapsible gas-bag F, so that the diaphragm—that is, the means which controls the valve C—may be variably positioned by the pressure within the generator, which pressure is transmitted to the diaphragm.

40 The valve rod or stem K is by preference screw-threaded when the form of valve K' shown in the drawings is employed. Obviously this particular form of valve is im- 45 material.

50 Other modifications may be made without departing from the spirit of the invention, as it should be understood that we do not intend to limit ourselves to the specific details 55 of construction shown in the drawings. For example, instead of employing a cam for operating the diaphragm-controlling lever any well-known mechanical means might be substituted that would accomplish the desired end.

55 If a leak should be developed within the apparatus or if for any reason it should temporarily fail to work properly, the user may instantly turn off the gas, whereupon the carbid-feed would be closed and locked, and he may thereupon proceed to correct the defect, or he may set the apparatus aside with perfect safety until such time as it is convenient to make the necessary repairs.

What we claim is—

1. In an acetylene-generator, separate holders for the gas-generating elements, feeding mechanism for the contents of one of said holders, automatic controlling means therefor and independent manual controlling means, 70 comprising a cam and a lever co-operatively connected to the automatic controlling means.

2. In an acetylene-generator, separate holders for the gas-generating elements, feeding mechanism for the contents of one of said 75 holders, automatic controlling means therefor, independent manual controlling means, comprising a rotatable shaft carrying a cam, and a lever operated by said cam, said lever being in co-operative engagement with said 80 automatic controlling means.

3. In an acetylene-generator, separate holders for the gas-generating elements, feeding mechanism for the contents of one of said 85 holders, automatic controlling means therefor and independent manual controlling means, comprising a rotatable valve-stem carrying a cam, and a lever coacting with said cam, said lever being in co-operative engagement with said 90 automatic controlling means.

4. In a gas-generating apparatus, a gas-generating chamber, a collapsible gas-chamber in communication therewith, an outlet in communication with said collapsible gas-chamber, a valve for said outlet, a cam on 95 the stem of said valve coacting with means for expanding said gas-chamber when said stem is moved to close said valve, and means for automatically controlling the carbid-feed said means comprising said collapsible gas- 100 chamber.

5. In a gas-generating apparatus, a gas-generating chamber, a collapsible gas-chamber in communication therewith, a feed mechanism automatically controlled thereby, an 105 outlet in communication with said collapsible gas-chamber, a manually-controllable valve for said outlet, a screw-threaded valve-stem for said valve, a cam on said valve-stem, and means between said cam and said collapsible 110 gas-chamber whereby when said valve is closed said collapsible chamber is expanded, and feed mechanism controlled by said collapsible chamber.

6. In a gas-lamp, a gas-generating chamber, a collapsible gas-chamber in communication therewith, a burner in communication with said collapsible gas-chamber, a valve in the passage to said burner, a cam on the stem of said valve coacting with means for expanding said gas-chamber when said stem is moved to close said valve, separate chambers for holding gas-generating elements and a valve automatically controlled by the diaphragm of the collapsible gas-chamber and 120 manually controllable by the cam.

7. In a gas-lamp, a gas-generating chamber, a collapsible gas-chamber in commun- 125

cation therewith, a burner in communication with said collapsible gas-chamber, a valve for the passage to said burner, a screw-threaded valve-stem for said valve, a cam on said valve-stem, and means between said cam and said collapsible gas-chamber whereby when said valve is closed said collapsible chamber is expanded, separate chambers for holding gas-generating elements and a valve automatically controlled by the diaphragm of the

collapsible gas-chamber, and manually by said cam.
